UNITED STATES PATENT OFFICE.

SAUL ARONSON, OF BROOKLYN, NEW YORK.

COIN-ACTUATED MECHANISM.

SPECIFICATION forming part of Letters Patent No. 760,722, dated May 24, 1904.

Application filed January 16, 1904. Serial No. 189,386. (No model.)

To all whom it may concern:

Be it known that I, SAUL ARONSON, a citizen of the United States, and a resident of the borough of Brooklyn, in the city and State of New York, have invented a new and useful Improvement in Coin-Actuated Mechanism, of which the following is a specification.

My invention relates to an improvement in coin-actuated mechanism, which mechanism is herein represented as adapted to control the movement of the valve-controlling shaft of a prepayment gas-vending machine—such, for instance, as that shown in the companion application filed by me on January 12, 1904, the serial number being 188,722.

The object of my invention is to provide a very simple and effective mechanism in which the liability of "beating" the machine is eliminated and in which a number of coins may be successively introduced to the mechanism and the driving-gear thereof continuously rotated a predetermined number of rotations.

A further object is to provide a device in which the coin is positively ejected from its interlocking engagement after the handle and driving-gear have become interlocked by other means.

A further object is to provide a device for preventing the insertion of coins after a predetermined number of coins have been inserted for a continuous operation of the mechanism.

A practical embodiment of my invention is represented in the accompanying drawings, in which—

Figure 1 represents the coin-actuated mechanism in front elevation, the parts being shown in their normal position ready to receive a coin. Fig. 2 is an edge view of the same. Fig. 3 is a face view of the driving-gear and its adjacent parts, showing the coin-pocket and the means for positively ejecting the coin therefrom in full lines in one position and in dotted lines in another position. Fig. 4 is a transverse section through the same in the plane of the line A A of Fig. 3 looking in the direction of the arrow. Fig. 5 is an inverted view of the front plate and the parts carried by the rotary handle, the parts being in a different position from that represented in Fig. 1. Fig. 6 is a detail top plan view of a suffi-

cient portion of the mechanism to indicate the means for preventing the insertion of coins to the mechanism after a predetermined number have been inserted up to the capacity of the mechanism, and Fig. 7 is a face view of the cam-gear which controls the movement of the means for closing the coin-chute.

The back plate is denoted by 1, the front by 2, which plates are connected and spaced the required distance apart by pillars 3, projecting from the back plate 1, and screws 4, extending through the front plate into engagement with the said pillars.

The driving-gear is denoted by 5, and it is mounted to rotate in proximity to the back plate 1 upon a stud-axle 6. This driving-gear 5 is provided with a laterally-extended annular flange 7 adjacent to the periphery of the gear, which flange is provided with an elongated slot 8 for the reception of a coin. A coin-pocket 9 is secured to the face of the driving-gear 5 a short distance inwardly from the slot 8, which pocket is fitted to receive a portion of a coin of predetermined size.

A coin-chute 10 is carried by the back plate 1 in position to direct a coin into the slot 8 and pocket 9 when the flange 7 is brought into position to bring the slot 8 beneath the inner end of the said chute.

The back plate 1 is provided with an opening 11, and the driving-gear 5 is provided with an opening 12, adjacent to the coin-pocket 9 and fitted to register with the opening 11 in the back plate when the driving-gear 5 is in position to receive a coin, so that if a coin of less diameter than the predetermined coin is inserted it will be caused to fall through the openings 11 and 12. This ejecting of the lesser-sized coin is insured by providing the bottom of the coin-pocket 9 with inclined edges 13, as clearly shown in Fig. 4.

The driving-gear 5 is shown herein as meshing with a pinion 14, fixed to a sleeve 15, which is loosely mounted on a sleeve 16, which in turn is loosely mounted on the valve-controlling shaft 17. A cam-gear 18 is fixed to the sleeve 16, and a spur-gear 19 is fixed to the shaft 17. A valve-controlling sleeve 20 is also mounted to slide longitudinally on the shaft 17. A rocking lever 21 is

mounted in a suitable bracket 22 on the spur-gear 19, one arm 23 of which lever is controlled by the cam 24 on the gear 18, and the other arm of which lever is engaged with the 5 sliding sleeve 20.

The coin-chute 10 is partially closed by an arm 25 when a predetermined number of coins has been inserted into the mechanism, which arm is operated as follows: The sliding 10 sleeve 20 is provided with a circumferential groove 26, within which a pin 27, uprising from the arm 25, travels. This arm 25 is pivoted at 28 to any suitable support, so that when the sleeve 20 is moved in one direction 15 the free end of the arm is rocked in a position to open the coin-chute and when the sleeve is moved in the other direction the arm is rocked in a position to partially close the chute. This sliding movement of the sleeve 20 is controlled by the shape of the cam 24, which engages the rocking lever 21. In the 20 present instance the parts are so timed that the arm 25 will be swung into position to partially close the coin-chute when the gear 18 25 has been rotated nearly one revolution. The gear 18 is provided with a greater number of teeth than the gear 19—in the present instance one more tooth—so that as the gears are rotated through a common pinion 29, carried 30 by an arm 30, fixed to the sleeve 15, the gear 19 will be caused to travel slightly faster than the gear 18.

The mechanism which I employ for imparting a rotary movement to the driving-gear 5 is 35 constructed, arranged, and operated as follows: A handle-shaft 31 is mounted to rotate in the front plate 2 of the mechanism, which shaft is provided with a suitable handle 32 for use in turning the same. This shaft 31 has 40 fixed thereto a ratchet-wheel 33, all of the teeth having shallow notches except one, which tooth is provided with a deep notch 34 for the purposes to be hereinafter explained. A spring-actuated pawl 35 is hinged at 36 to 45 the front plate 2 of the mechanism, the nose 37 of which pawl is fitted to successively engage the notches in the ratchet-wheel 33 as the handle is turned in the required direction. A retracting-spring 38 serves to yieldingly 50 hold the pawl in engagement with its ratchet-wheel. The handle-shaft 31 has keyed thereto a coin-engaging arm 39, which is provided with a laterally-turned portion 40, arranged to pass over the mouth of the coin-pocket 9 when no coin has been inserted therein, but fitted to engage the edge of the coin when the coin has been inserted into the said pocket. The coin-engaging arm 39 has hinged thereto 55 a latch 41, which latch is provided with a 60 nose or abutment 42. The driving-gear 5 is provided with a pin or abutment 43, arranged to be engaged by the nose 42 for locking the handle to the driving-gear at predetermined portions of the rotary movement of the handle-shaft, as will appear in the description of

the operation of the mechanism. This latch 41 is provided with a pin 44, which is fitted to travel around the periphery of a cam 45, fixed to the inner face of the front plate 2. To secure the positive inward movement of 70 the latch 41 at a predetermined portion of the rotary movement of the handle-shaft, a lug 46 is provided adjacent to the cam 45 to form, in conjunction with the cam, a short diagonal cam-groove 47, through which the pin 44 of 75 the latch is caused to pass. The pawl 35 is provided with a pin or lug 48, which is held in position to prevent the lug or abutment 43 on the driving-gear passing the same except when the pawl 35 is engaged with the deep 80 notch 34 in the ratchet-wheel 33.

The operation of the mechanism is as follows: A coin of predetermined size and value is inserted, through the coin-chute 10, into position within the pocket 9, carried by the 85 driving-gear 5. The handle 32, and thereby its shaft 31, is then turned in the required direction, causing the inwardly-turned portion 40 of the arm 39 to engage the edge of the coin, thus locking the handle to the driving-gear. As the rotary movement of the handle-shaft is continued the pin 44 of the latch 41 will be caused to ride up the incline 49 of the cam 45, thus throwing the nose 42 outwardly into position to engage the pin or 90 abutment 43 of the driving-gear. This will permit the removal of the coin from its interlocking engagement and allow it to drop out of the pocket by gravity when the driving-gear 5 is rotated a sufficient distance. 100 As the handle and gear approach the end of their first revolution the pin 44 will be positively led inwardly through the inclined cam-groove 47, thus releasing the nose 42 of the latch 41 from its engagement with the driving-gear and disconnecting the handle from the said gear. The position of the pin or lug 48 on the pawl 35 is such that it will remain 105 in the path of the pin or abutment 43 on the spur-gear until the gear has nearly completed 110 its revolution. This prevents the spur-gear from gaining momentum enough to carry it beyond a single revolution. As the handle-shaft completes its revolution the pawl 35 will be permitted to swing inwardly a sufficient 115 distance, because of the deep notch 34, to withdraw the pin or lug 48 from the path of the pin or abutment 43, thus leaving the gear in position to be again rotated by the interposition of a coin of the predetermined size 120 and value between the handle-shaft and said gear.

I provide the following mechanism to insure the ejecting of the coin if from any cause the coin should tend to stick within the pocket. 125 The stud-axle 6, upon which the driving-gear 5 is mounted, is provided with a stationary plate 50 interior to the said gear, which plate is provided with a pin 51. A sliding ejector-bar 52 extends across the axis of the driving- 130

gear and is provided upon the side diametrically opposite the coin-pocket 9 with an elongated slot 53, within which a pin 54, secured to the driving-gear 5, travels. The 5 other end of the ejector-bar 52 enters the coin-pocket 9, and as the driving-gear 5 is rotated the bar is moved in a direction to push the coin out of the pocket by providing the bar with a double cam-groove 55, within which 10 the pin 51, carried by the fixed plate 50, is fitted to travel.

What I claim is—

1. A coin-actuated mechanism comprising a rotary handle-shaft, a driving-gear fitted to be locked thereto by a coin during a partial revolution of the gear and auxiliary means for automatically interlocking the shaft and gear to complete the revolution of the gear. 15

2. A coin-actuated mechanism comprising a rotary handle-shaft, a driving-gear arranged to be interlocked therewith by a coin during a partial revolution of the gear, auxiliary means for automatically interlocking the gear and shaft for completing the revolution of the 25 gear and means for positively ejecting the coin at a predetermined point in the revolution of the gear.

3. A coin-actuated mechanism comprising a rotary handle-shaft, a driving-gear arranged 30 to be interlocked therewith by a coin during a partial revolution of the gear, auxiliary means for automatically interlocking the gear and shaft to complete the revolution of the gear and means for preventing the gear from 35 moving beyond a single revolution for the insertion of each coin.

4. A coin-actuated mechanism comprising a gear having a coin-pocket, a rotary handle-shaft provided with an arm arranged to engage the coin when in the pocket for imparting a partial revolution of the gear and auxiliary means for automatically interlocking the gear and shaft to complete the revolution of the gear. 40

45 5. A coin-actuated mechanism comprising a driving-gear, a rotary shaft arranged to be locked thereto by a coin during a partial revolution of the gear, an abutment carried by the gear, a latch carried by the handle-shaft and a fixed cam arranged to throw the latch into interlocking engagement with the abutment for completing the revolution of the gear.

6. A coin-actuated mechanism comprising 55 a driving-gear, a rotary shaft arranged to be interlocked therewith by a coin during a partial revolution of the gear, auxiliary means for automatically interlocking the gear and

shaft to complete the revolution of the gear, a ratchet carried by the shaft, a pawl engaging the same, the said pawl being arranged to prevent the gear from moving more than one revolution for the insertion of each coin. 60

7. A driving mechanism comprising a driving-gear, a rotary shaft arranged to be interlocked therewith by a coin and auxiliary means arranged to be brought into and out of interlocking engagement between the shaft and gear. 65

8. A coin-actuated mechanism having a coin-chute, a vending-mechanism shaft, a driving-gear therefor, a rotary handle-shaft, means under the control of a coin for locking the shaft and driving-gear and means for closing the chute after a predetermined number of 75 coins have been inserted comprising a device carried by the vending-mechanism shaft and an arm operated thereby. 70

9. A coin-actuated mechanism comprising a driving-gear, a rotary handle-shaft arranged 80 to be interlocked with the gear by a coin, a ratchet carried by the shaft having a deep notch between two of its teeth and a pawl arranged to engage the ratchet, the said pawl being provided with a pin or lug arranged to 85 engage the gear except when the pawl is in engagement with the deep notch in the ratchet.

10. A coin-actuated mechanism comprising a driving-gear having a coin-pocket therein, a rotary handle-shaft arranged to engage the 90 coin when in the pocket for imparting a partial revolution to the gear, auxiliary means for automatically locking the shaft to the gear to complete the revolution of the gear and means for positively ejecting the coin from 95 its pocket at a predetermined point in the revolution of the gear consisting of a longitudinally-sliding bar operated by the rotary movement of the gear.

11. A coin-actuated mechanism comprising 100 a rotary actuated member, a rotary actuating member fitted to be locked thereto by a coin during a part of the rotary movement of the members, and an auxiliary means for automatically locking the two members together 105 to permit the actuating member to complete the rotary movement of the actuated member.

In testimony that I claim the foregoing as my invention I have signed my name, in presence of two witnesses, this 9th day of January, 110 1904.

SAUL ARONSON.
